ATTORNEY

UNITED STATES PATENT OFFICE

ELLIS McWHORTER, OF ALGONA, IOWA

TOBACCO CAN

Application filed April 26, 1929. Serial No. 358,369.

This invention relates to a combined tobacco or cigarette box, burnt match and cigarette stub receiver.

A primary object of the invention is to provide a box of this character having a container at one end to receive and hold burnt matches and cigarette stubs whereby all danger of fire from dropping burnt matches and cigarette stubs is prevented and by means 10 of which children are protected against handling and smoking such stubs.

Another object is to provide a box of this character with a removable container of the character above mentioned which is yieldably 15 held within the box to adapt it to be removed for cleansing and other purposes and constructed to fit and be held in either end of the can to suit the convenience of the user and facilitate its insertion.

20 In carrying out these objects, the invention is susceptible of a wide range of modification without departing from the spirit or sacrificing any of the advantages of the claimed invention; there being shown in the 25 drawings for illustrative purposes a preferred and practical form, in which:

Figure 1 is a perspective view of a tobacco box constructed in accordance with this invention;

30 Fig. 2 is a transverse vertical section thereof; and

Fig. 3 is a perspective view of the match and stub container removed.

In the embodiment illustrated is shown a 35 pocket box 1 such as is used by smokers for holding cigarettes or smoking tobacco which is of the usual flat shape being substantially oval in cross section. This box 1 has hinged covers 2 and 3 at its respective ends one opening in one direction and the other in the opposite direction. Spaced inwardly from each end of the box is a circumferentially extending outstruck rib, which are respectively numbered 4 and 5. These ribs form stops 40 for the covers 2 and 3 as shown clearly in Fig. 2.

Removably mounted in the box is a container 6 shaped to conform to and fit within either end of the box 1, it being adapted to 50 be inserted and held in either end of the box

thereby facilitating its insertion since no matter which closure is opened the container will fit in the end exposed.

The ribs 4 and 5 of the box are spaced the same distance from the ends of the box and operate to receive and hold the container 6. 55

This container may be of any depth desired and is closed at its bottom and open at its top as shown in Figs. 2 and 3. It also has a circumferential rib 7 spaced from its upper edge the same distance as are the ribs 4 and 5 from the end edges of the box. This rib 7 is designed to spring into and fit the hollow or concave portion of the end rib of the box this interlocking engagement serving to hold the container in the box. When the container 6 is so disposed the cover at that end of the box serves as a closure therefor as shown in Fig. 2. 60

It will thus be seen that this box 1 open at both ends and equipped with hinged closures and with the hollow ribs 4 and 5 may have the container 6 mounted in either end, it being interchangeable to suit the wishes of the user. It is of course understood that when the container is positioned in the box as shown in Fig. 2 by opening closure 3 cigarette stubs or burnt match stems may be inserted in the container while cigarettes or tobacco may be placed within the body of the box and be accessible from the opposite end of the box by opening closure 2. 70

This box is extremely simple and cheap to manufacture and may be made of suitable material and decorated or ornamented in any manner desired. 75

Without further description it is thought that the features and advantages of the invention will be readily apparent to those skilled in the art, and it will, of course, be understood that changes in the form, proportion and minor details of construction may be resorted to, without departing from the spirit of the invention or its scope as claimed. 80

I claim:

1. A box of the class described open at both ends and provided with closures for such ends, a container for mounting in said box, both of the ends of said box and said con- 100

tainer being of uniform size and shape and having complementary interengaging means whereby the container may be interchangeably mounted in said ends.

5 2. A box of the class described open at both ends and provided each with a hinged closure, a container to fit in either end of said box, said box and container having interengaging means to hold the container in operative position in either end.

ELLIS McWHORTER.
